UNITED STATES PATENT OFFICE.

HARVEY RITCHIE, OF LUDLOW, KENTUCKY, ASSIGNOR OF ONE-HALF TO ERNST BOELZNER, OF NEWPORT, KENTUCKY.

STEAM-GENERATOR.

No. 922,817.

Specification of Letters Patent.

Patented May 25, 1909.

Application filed May 6, 1907. Serial No. 372,217.

To all whom it may concern:

Be it known that I, HARVEY RITCHIE, a citizen of the United States, and a resident of the city of Ludlow, in the county of Kenton and State of Kentucky, have invented certain new and useful Improvements in Steam-Generators, of which the following is a specification.

The several features of my invention and the various advantages resulting from their use conjointly or otherwise will be apparent from the following description and claims.

In the accompanying drawings making a part of this specification,—Figure 1 is a view 10 of a steam generator illustrating my invention,—parts of the structure being shown in elevation and parts in section. The section is a vertical central one of the said generator. Fig. 2 is a top view of this steam generator 15 below the dotted section line 2, 2, of Fig. 1. One of the several divisions which carries certain tubes for generating steam is here shown with the tubes. Fig. 3 is a top view of the generator partly in solid plan and 20 partly in section plan. The view shows the “top header” with connections to shell, also drybox for steam take off. Fig. 4 is a half plan view, showing three of the top and three of the bottom manifolds or arms, with- 25 out the tubes. Fig. 5 is a vertical central section of the central portion of the upper end part of the generator, and illustrating how the dry box, that is the receptacle for the dry steam may be made in a separate 30 piece from the part below which conveys the steam from the central steam generating apparatus to the outer peripheral chamber. Fig. 6 is a horizontal section taken in the plane of the dotted line 6, 6, of Fig. 5. Fig. 35 7 is a bottom view, showing one division of the several divisions of tubes present in the generator. This figure also shows a lower pipe for supplying water to the central vertical tube and the connection between the 40 same. Fig. 8 represents a vertical central section of one of the manifolds or arms, and of the connections between the manifolds, and also shows another of said connections in elevation. Fig. 9 is a view partly in ele- 45 vation and partly in section, illustrating a modification of the construction of the central tube located between the upper and lower parts of the generator. Fig. 10 is a plan view of that part of the lower portion of Fig. 9 below 50 the plane of the dotted line 10, 10 of Fig. 9.

Fig. 11 is a vertical central section of the device shown in Fig. 10, said section being taken in the plane of the dotted line 11, 11 of Fig. 10. Fig. 12 is a view partly in elevation and partly in section, illustrating another modification of the central pipes (tubes) located between the upper and lower parts of the generator. Fig. 13 is a plan view of that part of the device shown in Fig. 10 which is below the plane of the dotted line 13, 13 of Fig. 12. Fig. 14 is a vertical central section of the device shown in Fig. 13, said section being taken in the plane of the dotted line 14, 14, of Fig. 13.

I will now proceed to describe my invention in detail.

The outer side portion of the generator consists of a shell A. Within the space inclosed by this shell A is a second shell B, not far distant from the first. By these two shells A and B is formed a space C which from the bottom and as far up as the level C² performs the function of a chamber for holding water. Where the boiler is cylindrical, as it preferably is, this water chamber C may be termed the peripheral chamber C. In the present preferred construction, the bottom of this chamber C is closed at C³, and at the top at C⁴.

Inclosed within the shell B are present a number of tubes which when in use contain water, and are exposed to a heat external to them, and whereby the water in them is converted into steam. The preferred construction and arrangement of these tubes is illustrated in Figs. 1, 2, 5 and 6, and the said construction and arrangement are as follows:—In the center of the space inclosed by the shell B, is a large tube D extending vertically. As this tube D when in use requires a large amount of water to supply that which is withdrawn, a large supply tube E is provided, one end of which is connected to the lower part of this tube D, and the other end to the inner shell B, and thus a water supply passage is made between the central tube D and the chamber C.

Suitable and convenient means of coupling the tube E to the tube D and to the shell B are provided. In the present illustrative instance, these couplings consist of a cap D² at its upper end screwed to the lower end of the tube D, and of a coupling piece E² commonly termed a “runner nipple”, which by screw threads connects the cap D² to the tube 110

E. This tube E is connected to the shell B by a screw thread E³ in a common manner. The upper end of the central tube D is connected preferably by a screw thread D³ to the lower part of the central portion of a device which may be termed the top-header F. This top header has horizontal radial tubes G and H. The tube G affords a passage from the central vertical tube D to the peripheral chamber C at its outer end. Located at the terminus of tube G, in the said chamber C is a deflector G⁵, for directing the current of water passing up in tube D, and thence through the tube G downward in the said chamber C. The connection between the tubular arm G² of the header F and that remainder G³ of the tube G which extends out to the chamber C is preferably effected by a screw thread G⁴, as indicated. The tube H serves to connect the upper portion of the peripheral chamber C wherein steam accumulates within the drybox (or chamber K) of the header. This drybox K receives the steam generated in the entire apparatus and delivers it to a take off tube L. The latter delivers it for use in operating an engine or heating a radiator, or for whatever other purpose it is wanted.

The outer terminal of the tube H namely: where it intakes steam, is provided with a deflector H⁵ adapted to receive steam in chamber C coming from above down into this tube H, but closed against any inrush of steam from below. The advantage of this construction is that if steam were admitted from below and next to the boiling and foaming area of the chamber C, the upward and direct inrush of steam would carry into the tube H⁵ wet steam and often water.

The connection between the tubular arm H² of the header F and that remainder H³ of the tube H which extends out to the chamber C, is preferably effected by a screw thread H⁴ as indicated.

The header has any desired number of the radial tubes G and H. In the present instance, I have shown three of these tubes G and three of the tubes H.

It is to be understood that that part D⁴ of the header which constitutes the upper portion of the tube D, and which connects with the radial tubes G, is separated from that part of the header which constitutes the drybox K and with which the tubes H respectively connect by a single angulated diaphragm or partition M. But the header may be constructed in two pieces, in which case the partition M will remain substantially the same, but it will be composed of two partitions respectively marked M² and M³, located side by side, substantially as shown in Figs. 5 and 6. In such a construction, that part D⁴ of the header which connects with the tubes G is separable from that part K of the header with which the tubes H connect. The advantage of such a

contraction in two main parts as D⁴ and K, of the header is that all and any expansion or contraction of the respective tubes and their respective header portions will be permissible without pushing or retracting the chamber C out of its normal position. For this reason, when the generator is cold and out of use, a small space D⁵ is preferably present between the part D⁴ and the part K of the header. When the generator is heated, the parts of it expand, and this space D⁵ is eliminated for the time being, and while the generator continues hot.

Within the shell B there is, in addition to the central tube D, a series of tubes P. Below the tubes of the header F are a number of manifold or radial tubes N, and the upper ends of the tubes P are duly connected by coupling nuts P² to their respective radial tubes N. Below and within the shell B are a series of radial manifolds or tubes N². The lower ends of the said series of said tubes are respectively connected by coupling nuts P² to their respective radial tubes N². In order to utilize the space within the shell B, I provide a number of series of said tubes P. Thus to each of the upper radial tubes N, I connect two series of such tubes P and likewise to each of the lower radial tubes, I connect two series of such tubes P. Such series are indicated in Fig. 4. In Fig. 1, the second series of tubes P from radial tube N are shown starting from tube N, but are broken off, in order not to confuse what is shown in this figure. Preferably, in the one series, are four tubes P and in the other series from the same radial tube are three tubes P. It is understood that these two series of tubes P after encircling the tube N reach the lower radial tube N² preferably located in a vertical plane beneath said tube N last named. But in encircling the tube D, these two series travel around the tube D in opposite directions. Preferably the arrangement of all the series of tubes P belonging to and connected with the other upper radial tubes N and the lower radial tubes N² is like that already described in relation to the tubes N and N² last mentioned.

In Fig. 1, I have at the right of tube D shown a radial tube N and a radial tube N² without tubes P. The tubes P are omitted from these last named tubes N and N² for the sake of perspicuity. The upper radial tubes N and the lower radial tubes N² are firmly supported. The outer end portions of the lower radial tubes N² are screwed into the shell B. A passage from the chamber C through each tube N² into the tubes P that it carries is thus established. The outer end portions of the upper radial tubes N are secured in the shell B, and the terminal of each tube N extends into the chamber C. Each of these terminals is provided with a

deflector N³. Thereby a passage from the tube N into the chamber C is effected, and the deflector causes the wet-steam passing up through the tubes P and out through the tubes N to pass downward in the chamber C.

The mode in which my generator operates is as follows: The tube E, tube D, tubes P and chamber C (the latter through a suitable inlet C⁵) are filled with water as far as the line C². Fire is started within the shell B. Steam is rapidly generated. The steam in the tube D passes up and out of the radial tubes G, and downward into chamber C. The steam in the tubes P rises and passes into the adjacent radial tubes N and then goes through these tubes and out into chamber C, there being deflected downward by the deflectors N³. The steam generated in the chamber C and the steam collecting therein from the tube D and the tubes P passes up in the chamber C and finally finds exit by going up over the deflectors H⁵ of the respective tubes H and thence down into these tubes H. Thence it passes in a comparatively dry state into the drybox or compartment K. Here it loses the last portions of water which have been brought with it. It next issues from the drybox K into the take-off or delivery tube or pipe L, and passes to the place or places where it is to be used.

I will now proceed to describe the modification shown in Figs. 9, 10 and 11. By this modification, the several coiled tubes R are present and take the place of the one tube D heretofore described. The upper ends of these coiled tubes R respectively connect by appropriate coupling nuts with the chamber D⁴ already described. The lower ends of these coiled tubes R connect with a chamber R², preferably having a well R³. When this well R³ is present, the inlet water supply tube E will preferably be connected to this well R³ instead of being connected directly to the chamber R².

In Figs. 12 and 13, I have modified the direction of the tubes R of Fig. 9, so that they run straight vertically, and these tubes thus straightened I have indicated by the letter S.

Among the various advantages resulting from my invention may be noted the following:—cheapness and simplicity of construction. Ease by which the generator can be repaired. The screwing of the arms into the inside shell offers an advantage in that this construction creates a circulation of the water in the water leg of the boiler in every direction, independent of the central tube, tubes or coil pipes which are shown by Figs. 9 and 12. Staggering the tube connections in the several arms so that the tubes are made to run in opposite directions is an advantage, as a better contact with the flames is secured. Placing the drybox or steam take-off in the center of the boiler in the manner which I show by my drawings, I

claim as a superior advantage over other forms, as this secures the driest steam possible for service and also any condensation likely to form there is immediately converted into the driest of steam on account of being surrounded by the flames. By connecting the top header (one with the six arms) to the inside of the boiler, as shown, I consider also as an advantage in that it serves three purposes,—one for supporting the central tube, tubes or coil pipes. It also provides an outlet for the steam from the boiler to enter the drybox and also for the steam generated in the central construction back into the boiler. By taking the steam from the drybox or steam take-off in the center of the boiler as I show, is to my mind an advantage over the usual form of taking the steam from the side of the boiler, as by my arrangement no water whatever is carried out of the service pipe. By connecting the tubes in the way shown an advantage is gained over the method of expanding them, as I have no plugs opposite my tubes to burn off by the action of the fire. Another advantage which I claim is that with my construction I can carry a very low water line. The general construction of this boiler as shown is such that it is so easy to repair that it can be repaired without the aid of a skilled mechanic. This also is obviously a great advantage.

What I claim as new, and of my invention and desire to secure by Letters Patent, is:—

1. In a steam generator, the combination of concentric shells, a central series of generating tubes, upper radial tubes and lower radial tubes to which this central series of steam generating tubes is connected, the outer ends of the upper radial tubes extending into the steam space between the concentric shells and there provided with deflecting hood for deflecting the wet steam downward, substantially as and for the purposes specified.

2. In a steam generator, an outer peripheral chamber, a central series of steam generating tubes, upper radial tubes and lower radial tubes to which this central series of steam generating tubes is connected, the upper radial tubes extending into the peripheral chamber and at their ends in said chamber each provided with its deflector for deflecting the wet steam downward into said peripheral chamber, substantially as and for the purposes specified.

3. In a steam generator, the combination of concentric shells, a series of spirally curved generating tubes located within the inner of said shells, lower radial tubes and upper radial tubes, connected respectively to the lower ends and the upper ends of these spirally curved tubes, these radial tubes extending into the peripheral space of said concentric shells, and there each provided with a downwardly deflecting hood

substantially as and for the purposes specified.

4. In a steam generator, an outer peripheral chamber, a series of spirally curved generating tubes located within the inner shell of the said chamber, and upper radial tubes and lower radial tubes connected respectively to the upper ends and to the lower ends of these spirally curved tubes, 10 these radial tubes extending into the peripheral chamber and deflectors at those ends of these radial tubes that are within the chamber, substantially as and for the purposes specified.

15 5. In a steam generator, an outer peripheral chamber, a large central vertical tube, a water supply pipe at its lower end, radial tubes at its upper end connected at one end to this central tube and at the other end projecting into the peripheral chamber and each 20 of these radial tubes provided with a hood, substantially as and for the purposes specified.

25 6. In a steam generator, an outer peripheral chamber, a large central vertical tube, a water supply pipe at its lower end, radial tubes at its upper end connected at one end to this central tube and at the other end projecting into the peripheral chamber, a deflector at the end of each tube inside of the chamber, substantially as and for the purposes specified.

30 7. In a steam generator, an outer peripheral chamber, a large central vertical tube, a water supply pipe at its lower end, radial tubes at its upper end connected at one end to this central tube and at the other end projecting into the peripheral chamber, a series 35 of tubes spirally arranged around this large vertical tube, upper radial tubes and lower radial tubes respectively connected to the upper and lower ends of the spirally arranged tubes, within the peripheral chamber and each of these radial tubes provided with a 40 hood, substantially as and for the purposes specified.

45 8. In a steam generator, an outer peripheral chamber, a large central vertical tube, a water supply pipe at its lower end, radial tubes at its upper end connected at one end to this central tube and at the other end projecting into the peripheral chamber, a deflector at the end of each tube inside of the chamber, a series of tubes spirally arranged 50 around this large vertical tube, upper radial tubes and lower radial tubes respectively connected to the upper and lower ends of the spirally arranged tubes, within the peripheral chamber and each of these radial tubes provided with a hood, substantially as and for the purposes specified.

55 9. In a steam generator, an outer peripheral chamber, a large central vertical tube, a water supply pipe at its lower end, radial tubes at its upper end connected at one end

60 to this central tube and at the other end projecting into the peripheral chamber, a series of tubes spirally arranged around this large vertical tube, upper radial tubes and lower radial tubes respectively connected to the upper and lower ends of the spirally arranged tubes, and deflectors present at the ends of 70 said radial tubes, within the peripheral chamber, substantially as and for the purposes specified.

75 10. In a steam generator, an outer peripheral chamber, a large central vertical tube, a water supply pipe at its lower end, radial tubes at its upper end connected at one end to this central tube and at the other end projecting into the peripheral chamber, a deflector at the end of each tube inside of the chamber, a series of tubes spirally arranged around this large vertical tube, upper radial tubes and lower radial tubes respectively 80 connected to the upper and lower ends of the spirally arranged tubes, and deflectors present at the ends of said radial tubes, within the peripheral chamber, substantially as and for the purposes specified.

85 11. In a steam generator, an outer peripheral chamber, a large central vertical tube, a water supply pipe at its lower end, radial tubes at its upper end connected at one end to this central tube and at the other end projecting into the peripheral chamber, a deflector at the end of each tube inside of the chamber, a series of tubes spirally arranged around this large vertical tube, upper radial tubes and lower radial tubes respectively 90 connected to the upper and lower ends of the spirally arranged tubes, within the peripheral chamber, the series of spirally arranged tubes crossing each other in opposite directions, substantially as and for the purposes specified.

95 12. In a steam generator, an outer peripheral chamber, a large central vertical tube, a water supply pipe at its lower end, radial tubes at its upper end connected at one end to this central tube and at the other end projecting into the peripheral chamber, a series of tubes spirally arranged around this large vertical tube, upper radial tubes and lower radial tubes respectively 100 connected to the upper and lower ends of the spirally arranged tubes, within the peripheral chamber, the series of spirally arranged tubes crossing each other in opposite directions, substantially as and for the purposes specified.

105 13. In a steam generator, an outer peripheral chamber, a large central vertical tube, a water supply pipe at its lower end, radial tubes at its upper end connected at one end to this central tube and at the other end projecting into the peripheral chamber, a deflector at the end of each tube inside of the chamber, a series of tubes spirally arranged 110

- around this large vertical tube, upper radial tubes and lower radial tubes respectively connected to the upper and lower ends of the spirally arranged tubes, and deflectors present at the ends of said radial tubes, within the peripheral chamber, the series of spirally arranged tubes crossing each other in opposite directions, substantially as and for the purposes specified.
14. In a steam generator, a peripheral chamber, a central steam generating device or system provided below with a water supply inlet, a chamber for receiving the steam from said central device, radial tubes connected at one end with this chamber and at their other end with the peripheral chamber, a steam drybox, radial tubes connecting the drybox and the chamber, the said upper chamber of the central steam generating device interfitting with the drybox, and the radial tubes of the central steam generating device occupying half of the circular space, and the radial tubes of the drybox occupying the other half of the circular space, substantially as and for the purposes specified.
15. In a steam generator, a peripheral chamber, a central steam generating device or system provided below with a water supply inlet, a chamber for receiving the steam from said central device, radial tubes connected at one end with this chamber and at their other end with the peripheral chamber, a steam drybox, radial tubes connecting the drybox and the chamber and a deflector at the end of each of these last named tubes for compelling the steam for the drybox to rise above the deflector before entering the drybox, the said upper chamber of the central steam generating device interfitting with the drybox, and the radial tubes of the central steam generating device occupying the half of the circular space, and the radial tubes of the drybox occupying the other half of the circular space, substantially as and for the purposes specified.
16. In a steam generator, a peripheral chamber, a central steam generating device or system provided below with a water supply inlet, a chamber for receiving the steam from said central device, radial tubes connected at one end with this chamber and at their other end with the peripheral chamber, a steam drybox, radial tubes connecting the drybox and the chamber, the said upper chamber of the central steam generating device interfitting with the drybox, and the radial tubes of the central steam generating device occupying the half of the circular space, and the radial tubes of the drybox occupying the other half of the circular space, and a series of spirally arranged tubes for generating steam embracing this central steam generating device, and lower radial tubes and upper radial tubes connecting said spirally arranged tubes with said chamber, substantially as and for the purposes specified.
17. In a steam generator, a peripheral chamber, a central steam generating device or system provided below with a water supply inlet, a chamber for receiving the steam from said central device, radial tubes connected at one end with this chamber and at their other end with the peripheral chamber, a steam drybox, radial tubes connecting the drybox and the chamber, and a deflector at the end of each of these last named tubes for compelling the steam for the drybox to rise above the deflector before entering the drybox, the said upper chamber of the central steam generating device interfitting with the drybox, and the radial tubes of the central steam generating device occupying the half of the circular space, and the radial tubes of the drybox occupying the other half of the circular space, and a series of spirally arranged tubes for generating steam embracing this central steam generating device, and lower radial tubes and upper radial tubes connecting said spirally arranged tubes with said chamber, substantially as and for the purposes specified.
18. In a steam generator, a peripheral chamber, a central steam generating device or system provided below with a water supply inlet, a chamber for receiving the steam from said central device, radial tubes connected at one end with this chamber and at their other end with the peripheral chamber, a steam drybox, radial tubes connecting the drybox and the chamber, the said upper chamber of the central steam generating device interfitting with the drybox, and the radial tubes of the central steam generating device occupying the half of the circular space, and the radial tubes of the drybox occupying the other half of the circular space, and a series of spirally arranged tubes for generating steam embracing this central steam generating device, and lower radial tubes and upper radial tubes connecting said spirally arranged tubes with said chamber, substantially as and for the purposes specified.
19. In a steam generator, a peripheral chamber, a central steam generating device or system provided below with a water supply inlet, a chamber for receiving the steam from said central device, radial tubes connected at one end with this chamber and at their other end with the peripheral chamber, a steam drybox, radial tubes connecting the drybox and the chamber, and a deflector at the end of each of these last named tubes for compelling the steam for the drybox to rise above the deflector before entering the drybox, the said upper chamber of the central steam generating device interfitting with the drybox, and the radial tubes of the central steam generating device occupying the half of the circular space, and the radial tubes of the drybox occupying the other half of the circular space, and a series of spirally arranged tubes for generating steam embracing this central steam generating device, and lower radial tubes and upper radial tubes connecting said spirally arranged tubes with said chamber, substantially as and for the purposes specified.

tral steam generating device occupying the half of the circular space, and the radial tubes of the drybox occupying the other half of the circular space, and a series of spirally arranged tubes for generating steam embracing this central steam generating device, and lower radial tubes and upper radial tubes connecting said spirally arranged tubes with said chamber, the upper 10 of these radial tubes provided in the peripheral chamber with deflectors, substantially as and for the purposes specified.

20. In a steam generator, a peripheral chamber, a central steam generating device or system provided below with a water supply inlet, a chamber for receiving the steam from said central device, radial tubes connected at one end with this chamber and at their other end with the peripheral chamber, a steam drybox, radial tubes connecting the drybox and the chamber, the said upper chamber of the central steam generating device interfitting with the drybox, and the radial tubes of the central steam generating device occupying the half of the circular space, and the radial tubes of the drybox occupying the other half of the circular space, and a series of spirally arranged tubes for generating steam embracing this central 25 steam generating device, and lower radial tubes and upper radial tubes connecting said spirally arranged tubes with said chamber, the upper radial tubes of the steam generating series being located below the upper radial tubes of the central steam radiating device and of the radial tubes leading to the drybox, substantially as and for the purposes specified.

21. In a steam generator, a peripheral chamber, a central steam generating device or system provided below with a water supply inlet, a chamber for receiving the steam from said central device, radial tubes connected at one end with this chamber and at their other end with the peripheral chamber, a steam drybox, radial tubes connecting the drybox and the chamber, and a deflector at the end of each of these last named tubes for compelling the steam for the drybox to rise above the deflector before entering the drybox, the said upper chamber of the central steam generating device interfitting with the drybox, and the radial tubes of the central steam generating device occupying the half of the circular space, and the radial tubes of the drybox occupying the other half of the circular space, and a series of spirally arranged tubes for generating steam embracing this central steam generating device, and lower radial tubes and upper radial tubes connecting said spirally arranged tubes with said chamber, the upper of these radial tubes provided in the peripheral chamber with deflectors, the upper radial tubes of the steam generating series being located below the upper radial tubes of the central steam radiating device and of the radiating tubes leading to the drybox, substantially as and for the purposes specified.

22. In a steam generator, a peripheral chamber, a central steam generating device or system provided below with a water supply inlet, a chamber for receiving the steam from said central device, radial tubes connected at one end with this chamber and at their other end with the peripheral chamber, a steam drybox, radial tubes connecting the drybox and the chamber, the said upper chamber of the central steam generating device interfitting with the drybox, and the radial tubes of the central steam generating device occupying the half of the circular space, and the radial tubes of the drybox occupying the other half of the circular space, and a series of spirally arranged tubes for generating steam embracing this central steam generating device, and lower radial tubes and upper radial tubes connecting said spirally arranged tubes with said chamber, the upper 10 of these radial tubes provided in the peripheral chamber with deflectors, the upper radial tubes of the steam generating series being located below the upper radial tubes of the central steam radiating device and of the radial tubes leading to the drybox, substantially as and for the purposes specified.

23. In a steam generator, a peripheral chamber, a central steam generating device or system provided below with a water supply inlet, a chamber for receiving the steam from the said central device, radial tubes connected at one end with this chamber and at their other end with the peripheral chamber, a steam drybox, radial tubes connecting the drybox and the chamber, and a deflector at the end of each of these last named tubes for compelling the steam for the drybox to rise above the deflector before entering the drybox, the said upper chamber of the central steam generating device interfitting with the drybox, and the radial tubes of the central steam generating device occupying the half of the circular space, and the radial tubes of the drybox occupying the other half of the circular space, and a series of spirally arranged tubes for generating steam embracing this central steam generating device, and lower radial tubes and upper radial tubes connecting said spirally arranged tubes with said chamber, the upper of these radial tubes provided in the peripheral chamber with deflectors, the upper radial tubes of the steam generating series being located below the upper radial tubes of the central steam radiating device and of the radial tubes leading to the drybox, substantially as and for the purposes specified.

24. In a steam generator having radial arms located centrally, tubes running from these arms in opposite directions, the tube connections entering the arm on one side being staggered relatively to those entering the 100

105

110

115

120

125

130

arm at the other side, substantially as and for the purposes specified.

25. In a steam-generator, a group of tube-sections comprising series of lower and upper headers radially arranged around a common axis and connected by tubes coiled concentrically in alternate right and left vertical spiral courses around the common axis, substantially as set forth.

10 26. In a steam-generator, a group of tube-sections comprising series of lower and upper headers radially arranged around a common axis and tubes connected in alternation to opposite sides of the headers and coiled concentrically in alternate right and left vertical spiral courses around the common axis, substantially as set forth.

15 27. In a steam-generator, a tube-section

consisting of an upper and a lower header radiating from a common axis, and tubes connected in alternation to opposite sides of the headers and coiled concentrically in alternate right and left vertical spiral courses around the common axis, substantially as set forth. 20

28. In a steam-generator, a tube-section consisting of an upper and a lower header radiating from a common axis, and tubes connected in alternation to opposite sides of the headers and coiled concentrically in alternate right and left vertical spiral courses on 25 corresponding inclined planes around the common axis, substantially as set forth. 30
